NECKTIE THREADER

Filed April 9, 1928

UNITED STATES PATENT OFFICE

GUSTAV FISCHER, OF ELIZABETH, NEW JERSEY

NECKTIE THREADER

Application filed April 9, 1928. Serial No. 268,501.

Among the principal objects which the present invention has in view are: to provide means for threading the free end of a neck band of a neck tie through the knot 5 previously made in the body of the tie; to provide means for quickly securing the free end of said neck band; and to simplify and cheapen the construction of the threader.

10 Drawings

Figure 1 is a broad side view of a threader constructed and arranged in accordance with the present invention.

Figure 2 is an edge view of same.

15 Figure 3 is a view similar to Fig. 1, showing the end of the neck band of a tie secured thereto.

Figure 4 is a pictorial view showing a necktie arranged to receive the threader and neck band of the tie, in conjunction with the threader shown as in service.

Description

As seen in the drawings, the threader has 25 a contracted point 9 and a crook 10. The point 9 and crook 10 are at the opposite ends of the threader, which as seen best in Figure 1 of the drawings, is particularly constructed from wire, the sides 11 whereof are disposed in spaced and parallel relation. The point 30 9 is preferably formed by drawing the extremities of the sides 11 together and in this position, soldering or welding them together. The crook 10 is formed from the 35 looped end of the sides 11 and is overturned as shown best in Figure 2 of the drawings, so that the extremity of the crook is depressed to form a contracted passage 12 between the crook and the sides 11. The 40 crook 10 thus holds the second fold 13 of the tie neck band, thereby operating to prevent the same from pulling out of the loop.

The threader may be constructed of any suitable material, that preferred by me being what is known as piano wire.

As seen in the drawings, the body 14 of a neck tie is lightly knotted upon itself, leaving the necktie band 15, free. It is obvious that by doing this the location and therefore wearing spot of a neck tie can be varied to 50 suit the desire and taste of the person using the tie. When the tie is to be worn, the threader is adjusted to the free end of the neck band 15. To do this, the extremity 16 as shown best in Figures 3 and 4 of the drawings, is first slipped between the crook 10 and the sides 11. The threader is then rotated one complete revolution, the extremity 16 being held to prevent its pulling out from under the crook. The second fold of the 55 neck tie band is then slipped under the crook 10 and pulled over the extremity 16. When so secured, the neck tie band 15 may be threaded around and through the collar and the collar thus equipped may be adjusted as 60 in service. The threader is then removed from engagement with the neck-band until again the tie is to be placed as in service.

It will be understood that a tie when thus arranged is removed from service by holding the knot lightly but firmly while the neck-band is drawn upward therethrough. In this manner the knot is preserved for a further use, or on the other hand, the knotted portion of the tie may be shifted to 70 distribute the wear on the tie lengthwise of the body portion thereof.

By constructing the threader in the manner described, a smooth point such as indicated by the numeral 9 and a light but 75 servicable body is provided which will slip between the folds of the tie when being installed in service.

Claims:

1. A device as characterized comprising 85 spaced integral and compressible elongated body members having a contracted point at one end and a crook at the opposite end, said crook being formed by returning the material 90 of the body members upon itself, the terminus

of the crook and the body of the spreader being spaced apart.

2. A device as characterized comprising a body portion formed of wire, the strands whereof are disposed in parallel spaced relation, a crook at one end of said body portion, said crook being formed from said body portion by returning the joined end of the wires forming said body portion back upon itself, the end of the crook being juxtaposed in spaced relation to said body portion, and a point at the opposite end of said body portion formed by uniting permanently the free ends of the wire forming said body portion.

GUSTAV FISCHER.
